UNITED STATES PATENT OFFICE.

WILLIAM H. TAMS, OF TRENTON, NEW JERSEY.

DESIGN FOR A PLATE OR SIMILAR ARTICLE.

Application filed June 21, 1928. Serial No. 27,218. Term of patent 7 years.

To all whom it may concern:

Be it known that I, WILLIAM H. TAMS, a citizen of the United States, residing at Trenton, in the county of Mercer and State of New Jersey, have invented a new, original, and ornamental Design for Plates or Similar Articles, of which the following is a specification, reference being had to the accompanying drawing, forming part thereof.

In the drawing—

The figure is a plan view of a plate, showing my new design.

The ornamentation on the plate shown in the drawing is continued throughout.

I claim:

The ornamental design for a plate or similar article, as shown and described.

WILLIAM H. TAMS.
